UNITED STATES PATENT OFFICE.

ALBERT MUDRA, OF LINCOLN, NEBRASKA.

DESIGN FOR A BAIL FOR TRACE-BUCKLES.

No. 38,392.

Specification for Design.

Patented Jan. 1, 1907.

Application filed May 14, 1906. Serial No. 316,864. Term of patent 14 years.

To all whom it may concern:

Be it known that I, ALBERT MUDRA, a citizen of the United States, residing at Lincoln, in the county of Lancaster and State of Nebraska, have invented a new, original, and ornamental Design for a Bail for a Trace-Buckle, of which the following is a specification, reference being had to the accompanying drawing, forming part thereof.

The figure is a rear elevation of a bail for trace-buckles, showing my new design.

I claim—

The ornamental design for bail for trace-buckles as shown.

ALBERT MUDRA.
